UNITED STATES PATENT OFFICE.

MILLO L. STEARNS, OF BYWOOD, PENNSYLVANIA.

CLOTHESRACK.

Application filed January 2, 1923. Serial No. 610,120.

To all whom it may concern:

Be it known that I, MILLO L. STEARNS, a citizen of the United States, residing at Bywood, in the township of Upper Darby, 5 county of Delaware, and State of Pennsylvania, have invented certain new and useful Improvements in Clothesracks, of which the following is a specification, reference being had to the accompanying drawings.

10 This invention relates to clothes racks, and the object is to provide a device of this character which is extremely simple in construction, light and easily handled; and which is further characterized by its 15 adaptability to conversion into different forms of racks for convenient placement in whatever locations are available within the confines of a small room; and by its capability of being extended to a position for 20 erection over a radiator or other heating device for the purpose of suspending articles thereabove.

In addition to the foregoing this invention comprehends improvements in the 25 details of construction and arrangement of the correlated parts of what I now believe to be the preferred embodiment of my invention from among other possible forms and arrangements embraced within the 30 spirit thereof and the scope of the appended claims.

With reference to the drawings forming a part of this application, Fig. I is a view in perspective of a clothes rack constructed 35 in accordance with my invention and showing the same in folded position convenient for storage or shipment.

Fig. II is a view of the rack in perspective illustrating the parts arranged in one 40 of the extended positions of which the rack is capable.

Figs. III and IV are views in perspective of the rack with the parts extended to two other of its possible arrangements.

45 Fig. V is a view in transverse section of the rack in extended position to support the articles above a radiator; and

Fig. VI is a detail view on an enlarged 50 scale of the parts forming a joint between cooperating sections.

Proceeding to a detailed description of the device, it comprises a number of relatively movable sections which may be identified arbitrarily by the numerals 10, 11 and 55 12, indicating respectively a long section, an intermediate section and a short section,

utilizable and interchangeable as legs, supports and props according to the manner in which the sections are extended and placed.

60 The section 10 comprises a pair of parallel spaced runners 13 connected by means of rungs 14 forming supports upon which the articles are strung. The terminals of the runners 13 at one end of the section are connected to the ends of runners 15, constituting the section 11, through the medium of hinges 16, attached to the edges of the runners of both sections so as to permit relative movement of said sections to 65 folded position in contact, movement of said sections in an opposite direction being limited by endwise abutment of the runners, the abutting faces being beveled to permit the disposition of said sections out 70 of alignment or obliquely in one of the operative positions of the device. The runners 15 are likewise connected by means of rungs similar to the runs 14.

75 The section 12 comprises a pair of short 80 runners 17 which are pivotally connected to the runners 15 at points spaced inwardly from the hinges 16 thereof. The connection is preferably established through the medium of plates 18, one of each of which 85 is rigidly secured to one of the runners 15 to project laterally therebeyond for pivotal connection at 19 to the adjacent ends of the runners 17. If desired said pivoted ends of the runners 17 may be rounded and said 90 rounded ends faced with plates 20 to permit movement of the sections 11 and 12 without causing undue wearing of the parts. The runners 17 are likewise connected by means of rungs 14.

95 Referring to Fig. I it will be noted that the sections may be folded into compact relation and parallelism for shipment or storage.

100 The construction described is susceptible of use where a low support is desired. This is accomplished in the manner shown in Fig. II, from which it will be noted that the sections 10 and 12 are separated from the intermediate section 11 which is thus disposed vertically and the sections 10 and 12 extended in diverging relation to constitute props for the central section. The sections may be held against movement in this position by means of braces 21 consisting 105 of strips of metal permanently fixed at 22 in pivotal relation to the inner ends of the

runners 13 with their opposite ends notched laterally as at 23 to receive studs 24 extending from the inner sides of the runners 15. In a similar manner braces 25 are permanently connected to the runners 17 and adapted for releasable attachment to the runners 15 by means of other studs 24 extending from the latter. The structure is thus self-sustaining and affords a rigid support for clothing which may be readily strung along the rungs of the several sections.

Where the location affords a limited area of floor surface upon which to support the rack the latter may be extended vertically to the position shown in Fig. III by moving up the section 10 from the position in Fig. II to a position in alignment with section 11 and then again out of alignment until the meeting ends of the sections 10 and 11 abut, disposing the section 10 at a slight inclination to the vertical when section 11 is upright.

The section 12 remains in its former position and functions as a prop which extends the center of gravity well beyond the upper end of the section 10, so that clothes may be supported on all of the rungs against possibility of tipping or overbalancing the device. The braces 21, previous to adjustment of the device to this position are disengaged from the studs and reengaged upon other studs suitably located for the purpose.

As intimated above, the present invention is susceptible for use as a rack to be placed adjacent a radiator to suspend clothing thereabove. This position of the device is shown in Figs. IV and V and the parts are adjusted to that position as a natural change from the position shown in Fig. III by merely disengaging the braces 25 from the section 15, lifting the section 12 and reconnecting said braces to studs 24 extending from the runners 13 at points convenient for the purpose. In this position of the parts the section 11 is extended vertically and the sections 10 and 12 in contiguous relation and at an angle to lean against a wall back of the radiator. The rungs of the several

sections are thus available for the support 50 of articles in close proximity to the radiator.

Thus, it will be seen that I have provided a clothes rack which, by its novel construction is adapted particularly for use in small apartments, rooms or other confined locations where little space is available, with the additional attributes of lightness, compactness when folded and simplicity of structure.

Having thus described my invention, I 60 claim:

1. A rack comprising two hingedly connected sections of unequal length adapted for movement from mutual parallelism to acute or obtuse angled relation, a third section of less length than the shorter of the first named sections pivotally connected at one end intermediate the ends to the shorter of said first mentioned sections with capacity for relative angular movement, and releasable braces adapted to hold the respective sections in variously adjusted positions. 70

2. A rack comprising two sections each composed of side runners, means hingedly connecting together one end of the runners of each section with one end of the runners of the other section in such wise as to permit relative movement of said sections from parallelism into angular relation, rungs connecting the runners of the sections, a third section composed of side runners, means hingedly connecting one of the ends of the third section runners to the runners of one of the first mentioned sections at points intermediate their ends, and braces pivotally connected to the runners of certain sections with means for releasably connecting said braces to other sections at different points whereby the sections are held in different relatively adjusted positions. 85 90

In testimony whereof, I have hereunto signed my name at Philadelphia, Pennsylvania, this 28th day of December, 1922.

MILO L. STEARNS.
